PACKAGE FOR FURNITURE

John S. Kirby, Indianapolis, Ind., assignor to The
Hinde & Dauch Paper Company, Sandusky,
Ohio, a corporation of Ohio

Application December 12, 1941, Serial No. 422,626

5 Claims. (Cl. 206—46)

This invention relates both to a means and a method for packaging furniture, particularly adapted for desks, tables, cabinets and other items that have at least one large rigid surface, such as a desk top, which, by my invention, can be utilized to give the packing the necessary support and strength. It has long been customary to pack furniture, particularly desks, tables, cabinets and the like, with wrapping and padding such as excelsior, burlap and so on immediately surrounding the furniture, within the outer container, and bracing the outer cover by wood slats or similar elements which were kept from damaging the furniture by the padding. Later developments have had to do with carrying the weight of the furniture upon skids or frames which in turn supports an outer-covering, with little or no inner padding. However, such packages have not been entirely satisfactory for the reason that if the furniture is large or heavy or if the outer casing is subjected to strains such as result from the goods being laid in improper positions or having other articles piled on, the lack of inner support for the outer covering permits such casing to come into contact with the furniture. On account of this danger it has not been practicable to eliminate the inside wrapping even where the weight both of the furniture and of the outer cover is entirely carried by skids, and where the outer casing is of heavy corrugated board or similar material having a considerable amount of inherent strength.

A further difficulty has been that in types of furniture packing in which the weight is supported by skids or frames, the attachment of the furniture to such skids or frames has presented difficulties. In some instances the frames have been fastened to the feet of the furniture, for example by connections in the caster holes of the feet. In other instances the frames have been fastened to cross bars on the furniture by various sorts of connectors, and a number of other expedients have been employed. None of these have been entirely satisfactory, nor have eliminated the danger of marring the furniture, nor utilized the strength of the furniture as a support for the outer casing.

The purpose of my invention, then, is to avoid such difficulties as have been outlined above in connection with the prior methods, to obtain the advantages of a skid-supported packing without its disadvantages, to very greatly reduce the amount of interior packing required for the furniture inside the outer casing, and to hasten and simplify the packing operation. A further purpose

is to use the furniture itself in such relation to the outer casing as to brace such outer casing and use the strength of the furniture as the strength of the packing. Another purpose is to so relate the skid, the casing and the furniture that the skid does not have to be fastened to the furniture, but will serve its purpose by being fastened to the casing.

A further advantage of my invention is that the 10 elimination of such interior packing as large quantities of crumpled paper, burlap, excelsior, and the like removes a fire hazard. The fire hazard of conventional packing is so great that in many cities it is required that desks, cabinets, 15 tables and similar furniture be unpacked before being stored by the wholesale or retail dealer. This requirement occasions an otherwise unnecessary expense for handling, since large quantities of wrapping material have to be disposed of, 20 and the furniture has to be protected again in some way before being delivered to a customer; in fact has to be entirely repacked for out of town retail trade. Furthermore the unpacking results in the furniture in the warehouse requiring some 25 temporary protection against dust and dirt.

My invention, therefore, eliminates extra 30 handling, eliminates fire hazard, and greatly reduces the total amount of packing material required. At the same time it gives a quick and 35 expeditious method of applying a strong and durable packing in which the furniture may not only be safely shipped but also stored for an indefinite period and from which it need not be removed in the warehouse nor at any time prior to actual delivery to the customer.

The specific embodiment of my invention is 40 shown in certain drawings herewith and described in detail in the following specification, it being understood, however, that such drawings and description are of a preferred embodiment only, and are of an illustrative character; they may be modified both as to the sort of furniture to which applied and as to the details of the packing construction without departing from the principles 45 of my invention.

In the accompanying drawings:

Fig. 1 is a perspective view illustrating the first 50 stages of application of my improved packing to a desk;

Fig. 2 is a bottom view of the same, illustrating the final stages of closing the packing;

Figs. 3 to 7 inclusive are diagrammatic vertical 55 sections representing the successive stages of the packing operation by my improved method; and

Fig. 8 is an enlarged detail of the upper left corner of Fig. 4.

In certain of the drawings, and particularly in the diagrammatic views, the various panels and other elements of packing and padding material are shown slightly out of contact so that the relations of parts can more readily be seen.

In order to pack an article of furniture (hereafter referred to only as a desk by way of example), such desk 1 is set a few inches above the floor on horses 2, and the carton or casing 3, open at bottom and top, is slipped downward over it with top and bottom open. The casing is in most features an ordinary type slotted carton, having sides 4, 4 and ends 5, 5 secured by a boxmaker's joint 6, inner top laps 7, 7 and outer top half laps 8, 8, and bottom edge laps 9, 9 and 10, 10 which are mere narrow flanges. Either before, but more conveniently after such covering is applied, the top edges of the desk are covered at the corners with a small amount of suitable padding 11. The corner protectors illustrated by my co-pending application Serial No. 275,017, upon which Patent 2,271,265 was granted Jan. 27, 1942, are well adapted for the purpose although I do not limit my present invention to the use of any particular type of corner or edge padding. Such corner pads as mentioned afford an economical and satisfactory protection, giving ample strength and cushioning effect, with a minimum of material. If considered desirable soft wadded or crumpled paper may be used under the corner pads.

By way of further strengthening, a pad 12 may be fastened, preferably by adhesive, to the under side of one of the half laps 8 during the preliminary setting up of the carton. This pad is of substantial size and best applied diagonally so as to give a greater length for adhesion of the other lap 8 along the junction of the laps. This pad 12 gives a large surface to which the top laps 8 can be fastened by adhesive, as at 16, making a strongly fastened top without staples.

With the desk inverted on the horses and the carton on it, Fig. 3, the inner end laps 7 are now folded down in a manner which constitutes one of the important features of my invention, namely, they are each folded a little outside of mid-width, on a line 13, such fold line being parallel to the hinge line at the top of the end 5. Thus two panels 14 and 15 are formed of each inner lap, the outer, 14 being somewhat narrower than the inner, 15, so that 14 underlies 15 and overlies the corner protectors 11 when the carton is closed, as can be seen from comparison of Figs. 1, 3 and 8. Thus each lap 7 becomes a cushioning lap which bears inwardly upon the corner protectors 11 but is held up by them out of direct contact with the top surface of the furniture, and over which the outer laps 8 are closed and fastened as by adhesive 17. If the inner lap 7 is left flat the edge of such lap, bearing across the top of the table, frequently wears through any protective inner wrapping, such as wadded or crumpled paper, and mars the polished surface. One advantage of my present invention is the avoidance of possibility of such marring.

Still referring to Figs. 3 and 4, while the desk is still on the horses the outer half laps 8 are turned down over the cushioning laps and fastened thereto by the usual adhesive, such as silicate or starch or other adhesive, and at the same time the top half lap which does not carry the diagonal pad 12 is adhered to that pad. This

middle joint may or may not also be taped as desired. Next, Fig. 5, the desk in its top-closed carton is now turned upside down so that the legs are up in the air and the bottom flanges 9, 10 of the carton are upward. A bottom frame 18 of rough material is now laid upon the exposed feet of the desk, this frame having suitable cleats 19 or other arrangement whereby it fits loosely against the exposed feet, so that the feet always bear upon it. This frame 18 is made of boards of suitable width, perhaps three times the width of the feet, so as to give ample bearing surface, but is not fastened either to the feet or to any other portion of the furniture. After the frame 18 is placed the bottom flanges are now turned down upon the frame boards and nailed thereto as by large headed nails 20 or otherwise firmly secured. Preferably, to make a stronger package, outside cleats 21 are nailed over the end flanges 9, and into the inner cleats 19, all as seen in Figs. 5 and 6. The box is now ready for shipment or for storage as the case may be, but will preferably be handled standing on end, Fig. 7, where the shape of the furniture makes this convenient, as is usually true with a desk or table.

The desk top fits snugly inside the side walls of the carton by reason of the corner protectors which have a cushioning effect and give a snug fit, and there is no vertical movement, for the reason that at the top the desk is held by the corner protectors 11 and the cushioning laps 7 and at the bottom it is held by the wooden frame 18 which is held snugly upon the bottoms of the legs by the fastenings of the bottom flanges 9, 10 to such frame.

It will be understood that the invention above described is capable of modification in details and of application to suitable articles of furniture not specifically named herein, particularly those of generally rectangular outline and presenting solid tops or walls. The scope of the invention is set out in the following claims.

I claim:

1. A furniture package comprising a substantially rigid article of furniture a carton having side walls and a lapped top overfitting the top of said article of furniture, inside laps hinged to the top edges of opposed side walls, each having panels on their free ends again hinged parallel to said first hinge line and tucked under that panel which lies between the first and second named hinge lines, thereby constituting a cushion, and laps hinged to the top edges of the other side walls and closed over and secured to the upper exposed faces of said cushioning laps, and a bottom frame engageable with the base portion of the furniture, said frame being carried wholly by the carton and being attached to the bottom edges of said side walls.

2. A furniture package as set forth in claim 1, wherein corner pads of substantial thickness are applied to the furniture under said cushioning laps, thereby positioning said cushioning laps out of bearing upon the surface of the furniture.

3. A furniture package as set forth in claim 1 wherein a substantial portion of a separate panel is secured to the inner surface of one of said outer laps, leaving another substantial portion of said panel exposed, and the other of said outer laps is adhered to said exposed portion of said panel when said top is closed.

4. A furniture package comprising an article of furniture having a substantially rigid top and

supporting feet at the bottom thereof, a carton having side walls closely overlying the sides of said article, laps hinged to the top edges of the side walls and secured together in overlapping relation to form the top wall of the carton, pads interposed between the furniture and the top wall at the corners thereof, laps hinged to the lower edges of each side wall, and a frame bearing against the feet of said article of furniture, said frame being attached solely to the carton and comprising cleats attached to said bottom laps and to one another.

5. A furniture package comprising an article of furniture having a substantially rigid top and supporting feet at the bottom thereof, a carton 10

having side walls closely overlying the sides of said article, laps hinged to the top edges of the side walls and secured together in overlapping relation to form the top wall of the carton, the laps attached to two opposed side walls being beneath the laps of the other side walls and folded back upon themselves to form cushioning strips between the top of the article of furniture and the top walls of the carton, laps hinged to the lower edges of each side wall, and a frame bearing against the feet of said article of furniture, said frame being attached solely to the carton and comprising cleats attached to said bottom laps and to one another.

JOHN S. KIRBY.
